COMBUSTION-ENGINE METHOD AND APPARATUS

Application filed September 17, 1924. Serial No. 738,192.

(GRANTED UNDER THE ACT OF MARCH 3, 1883, AS AMENDED APRIL 30, 1928; 370 O. G. 757)

Heretofore in combustion or heat engines, much of the power producible heat has been lost by radiation, for instance to the cylinder and piston walls. From the cylinder walls 5 said radiated heat is imparted in substantial part for instance to the surrounding cooling medium or water, and the atmosphere. From the piston as well as large portions of the cylinder walls, said radiated heat is imparted 10 in substantial part to the, for instance in automotive or like motors, lubricating oil usually contained in the crank case, causing carbonization and disintegration and other losses of the lubricating characteristics of such oil 15 which endangers the working parts and requires frequent oil changes. Furthermore the pistons have been insufficiently lubricated, have had great areas of metal to metal contact with the cylinder walls and have been 20 subjected to great friction and wear. Furthermore, unconsumed fuel oil or gasoline has heretofore passed from the combustion chamber of the cylinder past the piston and its rings and into the crank case lubricating oil 25 where it is worse than wasted because it substantially lowers the lubricating characteristics of said last named oil and requires still more frequent change of such oil.

The primary object of this invention is to 30 provide an improved method of and apparatus for overcoming each of said substantial difficulties and thereby attaining greater efficiency, durability and economy.

My invention primarily relates to combustion 35 engine method and apparatus, and more particularly to a method of and apparatus for preheating the intake charge by the heat interchange thereto of the surplus heat of the juxtaposed cylinder and piston walls; as well 40 as by the heat interchange to the intake charge of the heat of the crank-case lubricant; as well as by the further preheating of the intake charge by the floating of each piston upon a surrounding relatively thin film of 45 the intake charge, which film is subjected to pressure throughout substantially the whole period when each piston is subjected to the compression and power stresses, and said surrounding film being formed of a multiplicity 50 of very thin and narrow alternate connected

films of different degrees of thinness and velocities of travel along the juxtaposed piston and cylinder surfaces, the friction of said higher velocity films accelerating the normal velocity of their adjoining lesser velocity 55 films of the intake charge. This also accomplishes the substantial lubrication of the juxtaposed piston and cylinder surfaces by applying thereto some of the fuel constituent of the intake charge, and further causes each 60 piston to be supported by said surrounding film of intake charge and therefore to require relatively small bearing surfaces between said pistons and cylinder walls.

A further object of my invention is to provide a method of and apparatus for varying 65 the valve timing while the engine is running.

To demonstrate the practical utility of my 70 said method, a related, improved and novel apparatus embodying my invention, and which may be used advantageously and 75 economically in practicing my said improved method as a unitary related invention, is provided to also serve as an example, to those skilled in the art, of the facility with which, 80 after becoming familiar with my method, of the many forms and kinds of existing engine apparatus, with or without substantial modification, may be employed in like or kindred production.

While my novel apparatus performs the 85 functions, apart from and except the heat essential factor, required to practice my improved method, yet many different constructed engines may, with or without substantial change, and with the essential heat factors common to all such engines, be readily employed in the economical and efficient practice of my novel method.

While my invention relates generally to 90 combustion engine method and apparatus, it further and more particularly relates in its method as well as apparatus aspects to the valves and valve combination incorporated in internal combustion engines and has for an 95 object the correct association of suction, compression, combustion, and exhaust periods necessary to produce the proper operation of said engine. Further objects of my invention, in its apparatus aspect, are as follows: 100

The proper shaping of the combustion chamber produced by correctly locating the valves; the cooling of the piston and pre-heating of the fuel mixture by injecting the fuel mixture through the piston into the combustion chamber; the correct variable timing of the exhaust valve opening and closure for the variable speeds of operation of the engine; the producing of one power stroke per revolution of the engine crank; the proper compression, combustion, and expansion of the fuel mixture including the correct relation between the gas volumes at the end of the compression and power strokes; the correct angularity of the crank journal during the compression of the fuel mixture that will allow the use of extreme high compression ratios; and the proper combination, arrangement and construction of the moving elements to produce the economical manufacture and use of said engines.

For the accomplishment of the foregoing and such other objects as may hereinafter appear, my invention consists in the construction, combination and arrangement of parts hereinafter described, and then sought to be defined in the appended claims. Reference is being made to the accompanying drawings forming a part hereof, and which shows merely for the purpose of illustrative disclosure, a preferred embodiment of my invention both in general service and aero service engines, it being understood that various changes may be made in practice within the scope of the claims, without digressing from my inventive idea.

I attain these objects by the mechanism illustrated in the accompanying drawings, in which:

Figure 1 is a vertical transverse section through a general service V shaped engine having valves in combination and operating periods according to my invention, and as would appear taken on the dotted line 1—1 of Figure 2.

Figure 2 is a broken plan and horizontal transverse section of Figure 1 with certain parts removed to illustrate more clearly the assembly of the valves, and as would appear taken on the dotted line 2—2 of Figure 1.

Figure 3 is a broken view in elevation and transverse section of one of the pistons as taken on the dotted line 3—3 of Figure 1.

Figure 4 is an enlarged vertical transverse section through the cylinder, piston and valve assembly as taken on the dotted line 1—1 of Figure 2 except illustrating the piston at the bottom of the combined inlet and power stroke and at the commencement of the combined compression and exhaust stroke.

Figure 5 is a fragmentary view similar to Figure 4 and illustrates the combined period of fuel injection and consumed gas ejection from the combustion chamber.

Figure 6 is similar to Figures 4 and 5 except illustrating the completion of the combined period of fuel injection and consumed gas ejection from the combustion chamber, and shows the position of the moving elements at the commencement of fuel compression within the combustion chamber.

Figure 7 is similar to Figures 4, 5, and 6 except illustrating the piston on the firing dead center at the completion of the fuel compression within the combustion chamber.

Figures 8, 9, and 10 illustrate a method of obtaining the variable timing of the opening and closure of the exhaust valve on the variable speed general service engine.

Figure 11 is a diagrammatic chart illustrating the relative positions of the crank journal of the general service engine during the various periods of operation of the combined inlet and power strokes, and the combined compression and exhaust strokes, the chart also illustrating other features and comparisons as are fully described herein-after.

Figure 12 is a broken transverse section through an aero service engine having valves in combination and operating periods in accordance with my invention and designed to operate at a more constant speed than the general service engine illustrated in Figures 1 to 11 inclusive.

Figure 13 is a fragmentary view of Figure 12 as taken on the dotted line 4—4 of Figure 12 and illustrates the method by which the exhaust cams may be mounted on the crank shaft on such an engine.

Figure 14 is a diagrammatic chart similar to Figure 11 except illustrating the relative positions of the aero service engine crank journal during the various operating periods of the combined inlet and power stroke, and the combined compression and exhaust stroke of my aero service engine.

With reference to the drawings and the figures and numerals thereon, similar numerals represent and indicate similar parts in the several views as follows.

Piston 1 has two diameters and external operating fits, the upper diameter being the smaller and being adapted to operate with a reciprocating motion within the cylinder bore 2, the lower and larger diameter piston being similarly adapted to operate within the cylindrical chamber 3. A cylinder liner 4 fits snugly within the cylinder body 5 and is shouldered at 6. The lower end of the liner secures the distance ring 7 within the upper and enlarged portion of the cylinder bore 3, the ring having a ground joint with the cylinder bore 3 and suitably sealed against the lower end of ring 4 in order to prevent leakage of fuel mixture into the fuel inlet chamber 8. The ring shaped fuel inlet or suction valve 9 is manufactured from a good grade of resilient piston ring stock, first being roughed

out, then split and forced open and bored to fit the smaller diameter and circumference of the piston 1. When ring 9 is finished and mounted in place on the piston it will have a tendency to spring inward and adhere to the piston. The ring is adapted to float between its seat 10 in the liner 4 and the distance ring 7 which limits the extent of opening of the inlet valve thus formed, and said ring 9 receives a reciprocating motion thus limited by said ring 7, from the friction of its inner surface with the piston. Constant communication is maintained between the fuel inlet chamber 8 and the fuel inlet manifold 11, and also between the exhaust chamber 12 and the exhaust manifold 13 as illustrated in Figures 1 and 2. The pin 14 is secured by a drive fit in the liner 4, the lower end of the pin extending between the ends of the inlet valve 9 thereby preventing the inlet valve from turning or rotating on the piston 1. The groove 15 in the bottom of the flange on the lower end of liner 4 is in the center of the valve seat 10 and extends around the same to within a short distance from the ends of the inlet valve 9, the port holes 16 forming constant communication between groove 15 and the inlet chamber 8. The poppet fuel by-pass or injection valve 17 is mounted within the head of the smaller diameter of the piston 1 and is held against its seat 18 by the bevel, resilient, snap ring 19. Ring 19 is manufactured from a good grade of resilient piston ring stock, the outer diameters being turned and finished considerably larger than the inner diameter of the seat 18. A short section of the circumference of the ring is then removed. The ring is mounted on poppet valve 17 and snapped into place within the head of the piston 1. The lower bevel of ring 19 is for the purpose of assisting in the insertion of valve 17 within the head of the piston and the upper bevel of ring 19 is for the purpose of forcing valve 17 into contact with its seat 18. The shoulder at the lower end of the upper bevel of ring 19 is for the purpose of retaining valve 17 in place in piston 1 and for preventing its accidental dislodgement therefrom. By screwing an eye-bolt into the threaded hole 20 in the upper portion of the valve 17, the valve and the snap ring 19 may be removed from the head of the piston 1, a screw driver or other similar instrument being used to close in the snap ring when the shoulder at the lower end of its upper bevel strikes the shoulder at the bottom of its tapering ring seat within the head of said piston. The primary fuel compression chamber 21 within the piston 1 is in constant communication with the annular chamber or compartment 22 via port holes 23 and 24, through the wall of the small diameter of the piston 1, and the communicating longitudinal grooves 25 in the outer periphery thereof. Chamber 21 is also in constant communication with the valve seat 18 via the slots 26

through the wall of the hollow large stem or lower portion of the valve 17.

The operation of the valves and the movement of the elements of the engine is as follows:

As the piston travels on its downward, combined inlet and power stroke, from the position illustrated in Figure 7, it draws the inlet valve 9 away from its seat 10 and into contact with the distance ring 7, opening thereby a communication between the annular chamber 22 and the inlet manifold 11 via the groove 15 in the peripherical valve seat 10, the port holes 16 and the inlet chamber 8. The displacement of the larger diameter and operating area of the piston causes a fuel inlet suction that fills chamber 22 with fuel mixture at approximately atmospheric pressure. The inlet communication is illustrated in Figure 4.

As the piston 1 starts upon its up-stroke it commences to compress in chamber 22 the charge intaken on its down stroke from charge inlet 11 and inlet manifold 8 through ports 16 in the peripherical groove 15, respectively through and in the valve seat 10 and through the then open valve ring 9. Said compressed intake passes from chamber 22 to chamber 21 in direct contact with the inner surface of the lining 4 of the combustion power portion of the cylinder, thereby accomplishing a substantial heat transfer, from the highly heater inner surface of said portion of said cylinder, to the said intaking fuel charge where the same volatilizes the less volatile constituents of said intaking fuel instead of wasting said transferred heat by radiation to the atmosphere. Furthermore said heat exchange enables each of the power cylinders and pistons to be kept down to a practical working temperature at far higher compression and consequently greater heat and fuel efficiency, than heretofore, was possible. Besides the thus intaken charge prevents crank case dilution because it comes in direct contact with and forces into chamber 21, through ports 23 and 24 the less volatile fuel condensed or ungassified in said power cylinder and which seeps along the walls of said power cylinder and through the piston rings.

Said intaking fuel in grooves 25 passes therefrom, through ports 23 and 24, into chamber 21 in the head of the power end of piston 1, where, as well as in its passage through grooves 25, said intaking charge cools the walls of said part of said piston and cylinder.

The fuel intake charge being intaken in direct contact with the inner surface of the cylinder and the outer surface of the piston provides a substantial lubrication of said surfaces due to the liquid and other lubricating characteristics of said charge. Furthermore the piston thus reciprocates on a relative thin film of air and fuel and hence reduces the

wear on the adjacent surfaces of said cylinder and piston and thereby prevents piston slap.

The longitudinal intake grooves 25, preferably uniformly spaced about the outer surface of piston 1, are each very shallow, while the clearance space between the top surfaces of said grooves 25 and the inner surface of their juxtaposed cylinder wall is substantially less than the depth of said grooves 25. I have devised this structure in order that the intake charge may, throughout substantially the intake cycle, be passed at substantially different velocities in a multiplicity of closely spaced and preferably connected very thin films or streams of different degrees of thinness, with the highest velocity being in the films or streams flowing through said grooves 25, and the lesser velocity being in the films or streams flowing through the intermediate clearance spaces. Each of said longitudinally flowing films or streams are connected and closely spaced apart so that the friction between said films of substantially different velocities will accelerate the lesser normal velocity of said thinnest films or streams flowing longitudinally through said clearance spaces. Said films or streams of the intake charge, so functioning, accomplish a substantial heat interchange thereto of the surplus heat of the inner surface of the cylinder wall and the outer surface of the piston, which, with their said thinness, velocity and friction, substantially raises the temperature of the intake charge.

Previous to said heat interchange the temperature of the intake charge had been substantially lowered by the vaporization of the fuel oil into said charge.

Said temperature raise of said films or streams of the intake charge produces a dryer gas and a more intimate and stable mixture of the fuel and air constituents of the intake charge in the combustion chamber, and produces more power from a given fuel with far less liability to crank-case dilution and other fuel wastes.

The pressure of said films or streams of the intake charge surrounding the piston, and which pressure is present during the intake as well as the power cycles, further substantially tends to stabilize each piston in the sense that the same requires substantially less surface area directly bearing upon the inner surface of the cylinder wall as said pressure of said films or streams of the intake charge surrounding the piston substantially tends to support said piston in definite relation to the cylinder wall, while said resulting substantially lesser bearing area at each end of each piston also performs the added function of confining said films or streams of the intake charge therebetween so that the travel of the piston will bring said films or streams into contact directly with substantially all

of the interior surface of the cylinder barrel at different times in each cycle.

During the same downward stroke of piston 1, combustion and expansion of the fuel mixture delivered to and compressed within the combustion chamber 27 on the previous up stroke, takes place within combustion chamber 27, the force of the combustion and expansion of the fuel mixture being exerted against the smaller diameter and operating area of piston 1. As the piston nears the end of its downward stroke the exhaust valve 28 is mechanically forced from its seat by the cam 41 and a pushrod and rocker arm arrangement. The consumed fuel mixture or gas escapes from combustion chamber 27 into the exhaust chamber 12 and the exhaust manifold 13. The open position of said exhaust valve 28 is illustrated in Figures 4 and 5. As the piston 1 travels on its upward, combined compression and exhaust stroke from the position illustrated in Figure 4, it draws inlet valve 9 away from the distance ring 7 and into contact with the valve seat 10 thereby closing the communication between chambers 8 and 22 thus preventing the fuel mixture charge within chamber 22 from escaping. The fuel charge within chambers 22 and 21 is compressed by the larger diameter and operating area of the piston within the cylindrical chamber 3. This compression causes valve 17 to lift automatically from its seat 18, thereby opening said fuel mixture injection communication ports 26 between chambers 21 and 22, and combustion chamber 27. Also, during the upward travel of the piston 1, the consumed fuel mixture or gas within combustion chamber 27 continues to pass into exhaust chamber 12 and exhaust manifold 13 via the exhaust valve 28, the gases ejected from combustion chamber 27 by the upward travel of the smaller diameter and operating area of the piston within the cylindrical chamber 2, and by the fuel mixture charge being injected therein from the chambers 21 and 22 as previously described.

Figure 6 illustrates piston 1 at the mid-point of its upward stroke. In this position, while operating under one-half stroke as the full fuel charge per cylinder per revolution of the engine crank, the exhaust valve 28 is mechanically and the fuel injection valve 17 is automatically closed, the chambers 21 and 22 and the combustion chamber 27 being filled with the fuel mixture at this instant at approximately the same or a trifle above the atmospheric pressure. The automatic closing of the valve 17 is due to the equalizing of the fuel mixture pressures within the chambers 21, 22 and 27, and to the smaller clearance space and higher compression ratio of the smaller diameter and operating area of the piston as compared with the larger clearance space and lower compression ratio of the

larger diameter and operating area of the piston.

As the piston 1, travels upward from the position illustrated in Figure 7 further compression of the fuel mixture takes place in chambers 21 and 22 that are in communication with or a part of the larger diameter and operating area of the piston 1, and in chamber 27 that is in communication with the smaller diameter and operating area of piston 1. 10 Valve 17 is kept closed because the pressure above it exceeds that below it, due to the fact that the relatively large ports 24 through the wall of the small diameter of piston 1 and near its center are closed by ring 9 and liner 2 during substantially the latter half of the up-stroke of piston 1, and the grooves 25, communicating with said ports 24, are of insufficient area, in the short time of the residue 15 of the up-stroke of the piston 1, to permit much of the mixture, then being compressed in chamber 22, to enter the chamber 21 through said ports 24 or through the upper tier of like ports 23 through the upper portion 20 of the wall of piston 1.

In reference to Figures 3 to 6, each piston 1 is provided with a conical dome wall 1^a, over its pitman and its bearing 66, which is preferably integral with a wall 1^b extending 25 between said bearings 66 in substantially parallel relation to the skirt or outer wall of the piston and terminates in an angular wall 1^c extending outwardly to, and preferably integral with, the piston skirt or outer wall 30 and with said wall 1^b.

Said wall 1^b joins the piston skirt on the side of the row of ports 24 most removed from the row of ports 23.

Said walls 1^a, 1^b and 1^c form a gas tight 40 cavity in the power end of each piston 1, which cavity is entered only through ports 23 and 24 and outletted through valve 17, while said walls seal the opposite end or open mouth of each piston 1 from the passage of 45 any of the splashed lubricant in the crank-case, and which lubricant is adapted to be splashed onto and over said walls 1^a, 1^b and 1^c and pitman bearings 66.

In the continued operation of the engine 50 said lubricant becomes heated by heat interchange from the combusted gases, and it is desirable, for economy and efficiency of operation, to cool said lubricant and said bearings 66. This is accomplished by the intake 55 charge flowing into the angular ports 24 and along said angular wall 1^c, thence against the relatively different angled wall 1^b, which tends to deflect same against the inner surface of the piston skirt, which tends to deflect same 60 toward and along said angular wall 1^a. This tends substantially to cool said walls 1^a, 1^b and 1^c and the other walls of said pistons with which said lubricant comes in contact and interchanges to the intake charge the 65 heat of said lubricant and prevents substan-

tial heat interchange to said lubricant of heat from the combusted gases, which latter is instead imparted to the intake charge, all to the betterment of said lubricant and intake charge.

It will be observed in Figures 4, 5 and 6, 70 that the piston ports 23 and 24 are moved at varying depths into their respective cylinders, and that said ports are sealed, but for said films or streams of intake charge, a substantial period before the piston reaches its outward dead center. After the closure of each piston valve 17 the further outward movement of each piston, in the charge compression cycle, substantially increases the 75 pressure in the explosion chamber of the cylinder as well as in the piston cavity and its surrounding films, the latter being the lesser pressure due to the lesser volume of the space 22, but said lesser pressure is exerted against a greater area of said piston than is said greater pressure. Said pressure of said films surrounding each piston is substantially maintained in varying degrees 80 throughout the major parts of the compression and power cycles wherein is exerted the greatest pressure in the combustion chamber of the cylinder, and said films pressure is so maintained throughout the major lateral area of each piston, rendering the pistons 85 more frictionless and requiring lesser bearing surfaces, which said surfaces function as well to seal or prevent the spread of said films beyond the area of the pistons.

When the piston reaches the top dead center position as illustrated in Figure 7 the pressure of the fuel mixture within the combustion chamber 27 should be approximately 135 pounds absolute, and the fuel mixture pressure within the primary compression 90 chambers 21 and 22 should be approximately 40 pounds absolute. As the piston 1 nears or passes over the dead center position illustrated in Figure 7 ignition of the compressed fuel charge within chamber 27 occurs, and 95 as said piston commences its succeeding downward stroke and prior to the drawing of the inlet valve 9 from its seat 10, a slight re-expansion of the compressed fuel mixture occurs within the chambers 21 and 22. 100 The series of periods as just described are 105 then repeated.

The following is a summary of the stroke period operations described in the foregoing 110 description of the operation of the valves and moving elements of the engine. On the down stroke of the piston, combustion and expansion of the fuel mixture charge in chamber 27, followed by the release of the consumed 115 remains of the charge through exhaust valve 120 28. During the same down stroke of the piston a slight re-expansion of the compressed fuel mixture occurs followed by an inlet suction of a fresh charge of full mixture into the 125 primary fuel compression chambers 21 and 130 22.

22. On the first part of the succeeding up stroke of the piston, the fresh fuel mixture charge, taken into chambers 21 and 22 on the preceding down stroke, is compressed and is injected into combustion chamber 27 via the valve 17. During the same period of upward stroke of the piston the consumed fuel mixture passes from the combustion chamber 27 to the exhaust via the exhaust valve 28, the residue of the consumed fuel mixture remaining adjacent open exhaust valve 28 being ejected by the fresh fuel charge being injected into the lower part of chamber 27 and by the upward stroke of the smaller diameter and operating area of the piston 1.

In constructing engines with the type of valve combination and operating periods and to use one-half stroke as the full fuel compression and consumption charge per cylinder per revolution of the crank shaft as described in the foregoing and as illustrated in Figures 1 to 10 inclusive, the one-half stroke displacement of the larger diameter and operating area of the piston 1 should equal the one-half stroke displacement of the smaller diameter and operating area of the piston plus the volume of the combustion chamber 27 with piston on top dead center, and enough additional displacement to overcome the tension of the snap ring 19, the pressure of the consumed gas in chamber 27, and to lift the valve 17 from its seat 18. The compression ratio of the smaller diameter and operating area of the piston of such an engine may be from 5 to 5.5 and the compression ratio of the larger diameter and operating area of the piston may be from 2 to 2.5 both of said ratios to be computed from one-half piston stroke, as these are found in my experience to give good results.

With reference to Figures 7, 8, 9 and 10, the variable timing of the exhaust opening and closure of the general service type engine is as follows: The exhaust cam shaft 30 is operated by the crank shaft 31 through the helical gears 32, 33, and 34, the gear 32 being secured to the crank shaft 31. The gear 33, being an idler gear is of extra width. The gear 34 is secured to and shiftable longitudinally with the cam shaft 30 by lever 39 due to said gear having mounted in a groove in its hub a thrust collar 35 that is journaled in and operated by shifting yoke 36, which in turn is rigidly keyed to the shaft 37. Shaft 37 is journaled in the casing 38 and is operated manually by the external lever 39. Shaft 37 also has the fuel throttle levers 40 mounted thereon. The lever 39, gear 34 and cam shaft 30 are shown in the full open fuel throttle position in Figure 1 and shown in full advance exhaust opening position in Figure 1. The longitudinal shifting of the cam shaft 30 and gear 34 giving the exhaust cams 41 that are integral with the shaft 30, an advance or retard rotation due to the angle

of the teeth in the helical gear 34 is illustrated in Figures 8 and 9. This advance or retard rotation of the shaft 30 and the cams 41 effects more particularly the opening of the exhaust valve, the variation in timing of the exhaust valve closure being controlled more by the longitudinal tapering of the cam 41 and the longitudinal shifting of the shaft 30.

In reference to the diagrammatic chart Figure 11, circle 42 represents the travel of the crank journal in the V shaped general service engine, the circle 43 shows the approximate location of the crank journal in degrees of rotation during the functions of the various periods and operations. Line 44 represents the top and bottom dead centers of crank travel. Dotted line 45 represents the piston travel during the compression of the fuel within the combustion chamber while operating under full fuel charge which in this case is one-half stroke for a full fuel compression and consumption charge per cylinder per revolution of crank shaft. Dotted line 46 represents the lineal clearance of the piston at the top end of its stroke or the amount of clearance necessary to form the combustion chamber when that chamber is the same diameter as the cylinder and the compression ratio of the engine is 5.5, computed from one-half stroke. Dotted line 47 represents the power stroke under full power and the dotted line 48 represents a similar stroke under closed fuel throttle. Circle 49 represents the crank travel of an ordinary engine. The full stroke compression of such engine is illustrated by the dotted line 50, it being equal in length to the one-half stroke compression line 45 described in the foregoing. Dotted line 51 illustrates the length of the power stroke of an ordinary engine as compared with its compression stroke 50 and with the power stroke line 47 described in the foregoing. Dotted line 52 represents the lineal clearance space of the piston of an ordinary engine in top dead center position, that is represents the combustion chamber of said ordinary engine when using a compression ratio of 4.5. Dotted line 53 represents the crank angle position at which the compression pressures in the combustion chambers of the ordinary engine using a compression ratio of 4.5 and a full stroke compression and fuel consumption charge per cylinder per revolution of crank shaft are equal to the compression pressure in the combustion chamber of a general service engine as per my invention, using a compression ratio of 5.5 and one half stroke as the full fuel compression and consumption charge per cylinder per revolution of crank shaft. In arriving at the location of this position the compression ratio of the ordinary engine is computed from full stroke and the compression ratio of my type engine is computed from

one-half stroke. It will be seen from the preceding description of the dotted line 53 and to the compression ratios 4.5 and 5.5 of the two engines that an extreme high compression ratio may be used on engines constructed in accordance with my invention without the usual serious regard being given danger of pre-ignition of the fuel mixture during compression. Arc 54 represents the full open throttle fuel suction period and arc 55 represents the closed throttle fuel suction of a general service engine built in accordance with my invention and using one-half stroke as the full fuel compression and consumption per cylinder per revolution of the crank shaft, the fuel suction occurring within the chambers 21 and 22 as previously described and as illustrated in Figure 4. The dotted arcs 54 and 55 represent a certain amount of re-expansion of the compressed fuel mixture within chambers 21 and 22 prior to opening of the inlet valve 9 and prior to the true commencement of said fuel suction. Arcs 56 and 57 represent respectively the full and closed throttle power strokes of my general service engine. The combustion of the fuel during the power strokes occurs within the combustion chamber 27 during the same downward strokes as the similar full and closed throttle fuel suction periods previously described. The full and closed throttle periods of the primary compression and fuel by-pass within and from the chambers 21 and 22 of my general service engine are represented by arcs 58 and 59 respectively. The full and closed throttle periods of the ejection of the consumed fuel mixture or gas from the combustion chamber 27 of my general service engine are represented by the arcs 60 and 61 respectively, the consumed fuel ejection occurring during the same crank rotation period as the similar full and closed throttle primary fuel compression within and by-pass or ejection from the chambers 21 and 22 as previously described. The full and closed throttle periods of the fuel compression within the combustion chamber 27 of my general service engine are represented by the arcs 62 and 63 respectively. The degree of fuel ignition advance range for full throttle of my general service engine is represented by the arc 64 and the degree of fuel ignition advance range for closed throttle operation is represented by the arc 65. Means (not illustrated) are provided for preventing fuel ignition from occurring prior to the exhaust valve closure while operating my engine under reduced or closed throttle.

With reference to Figures 3 and 4, the piston pin 66 illustrated therein is a drive fit within piston 11, the pin being shouldered at 67. It is prevented from backing out therefrom or turning therein by the screw 68. It is necessary that piston pin 66 be secure and a

pressure tight fit be made between it and the piston 1 owing to the pressure of the compressed fuel mixture in contact with the ends of the piston pin or pins.

It is understood that certain engines constructed for and operating under conditions that are favorable in land and marine or general service would not be suitable for aero service and vice-versa as general service engines usually operate under varying loads and speeds and aero service engines under almost constant loads and speeds and at full open fuel throttle. I have therefore supplied a different valve operation to be used in each type or types of engines. The engine illustrated in Figures from 1 to 11 inclusive is designed for general service conditions and to operate under the usual varying fuel charge ranging between closed and open fuel throttle at which such engines usually operate. The general service engine has variable exhaust opening and closing positions according to the amount of throttle used and also has an extreme long power stroke as compared with the diameter of its cylinder bore and to the full throttle fuel charge consumed per cylinder per revolution of the crank shaft. The engine is designed to use a fuel compression ratio of 5.5 and one half stroke as the full fuel compression and consumption charge per revolution of crank shaft.

The engine illustrated in Figures 12 to 14 inclusive is designed for aero service conditions. As such an engine operated under almost constant fuel charge and speed conditions, I have provided a constant non-variable exhaust opening and closure. The exhaust valve operating cams of such an engine are advantageously mounted and secured on the crank shaft as illustrated in Figures 12 and 13, each of the exhaust valve cams 69 operating the exhaust valves of the series of cylinders at the respective ends of the crank shaft 70. I design the aero service engine to have a short power stroke as compared with its cylinder bore but a long power stroke as compared with the full fuel throttle compression and consumption fuel charge per cylinder per revolution of the crank shaft. I also design the aero service engine to have a fuel compression ratio of 6 and one-fourth stroke as the full fuel compression and consumption charge per cylinder per revolution of the crank shaft. The speed and compression ratio of the aero service engine being higher than the speed and compression ratio of the general service engine, also the fuel consumed per cylinder per revolution of the crank shaft as compared with the length of the power stroke being the more economical in the aero service engine. Owing to the construction of both engines for their respective duties the aero service engine would develop more horsepower in foot pounds per

pound of weight than the general service engine.

Figures 12, 13 and 14 illustrate an air cooled service engine having valves in combination and operating periods in accordance with my invention. Twelve stationary cylinders, A to L inclusive, are arranged in two circles and in series around the crank shaft 70. Each cylinder is lettered alphabetically from the top to center cylinder to the right in the direction of rotation of the crank shaft 70. The pistons in the cylinders B, D, F, I and K are shown on their inward or combined power and fuel suction strokes, the piston in cylinder A being on its top or outward dead center and at the commencement of its combined power and fuel suction stroke, the piston in the cylinder G being on its inward dead center and about to go outward on its combined exhaust and fuel compression stroke, and the pistons in the cylinders C, E, H, J and L being on their outward or combined exhaust and compression strokes.

In constructing an engine of this type of valve and period combination and using one-fourth stroke as the full fuel compression and consumption charge per cylinder per revolution of the crank-shaft, as illustrated in Figures 12 and 14, the following relations between the various elements should exist: three-fourth stroke displacement of the larger diameter and operating area of the piston should equal one-fourth stroke displacement of the smaller diameter and operating area of the piston plus the area of the combustion chamber 27 with the piston 1 on its top or outward dead center, and enough additional displacement to overcome the tension of the snap ring 19, the consumed gas pressure within chamber 27 and to lift the valve 17 from its seat 18. The compression ratio of the smaller diameter and operating area of the piston of such an engine should be from 5.5 to 6, and the compression ratio of the larger diameter and operating area of the piston should be from 2.5 to 3, both ratios to be computed from one-fourth stroke fuel charge as the duration of the compression within the combustion chamber 27 is from three-fourths stroke to outward dead center.

In engines having a valve period combination in accordance with invention, the width of the annular space or chamber 22 is reduced by a reduction in the portion of the full stroke used for full fuel charge compression within the combustion chamber 27. This makes it possible (as illustrated in the aero service engine in figures from 12 to 14 inclusive) to eliminate the distance rings 7 by allowing the ring inlet valve 9 to rest (during the inlet period) on the upper edge of the cylinder bore 3, the grooves 71 being provided by milling into the edge of the cylinder bore

3 to allow a non-restricted passage of the fuel mixture by the outer edge of valve 9.

The following is a description of the dia-
grammatic chart Figure 14 of the aero serv-
ice engine operating periods. Circle 72
70 represents the rotation of travel of the crank
journal. Line 73 represents the dead center
positions of the piston and crank journal.
Arc 74 represents the power stroke period
and arc 75 represents the fuel inlet or suc-
tion period stroke. Both the power and fuel
suction periods occur on or during the same
downward or rather inward stroke of the
piston. Arc 76 represents the release and
ejection of the consumed fuel mixture from
the combustion chamber 27. Arc 77 repre-
sents the primary compression and the ejec-
tion of the fuel mixture charge from the
chambers 21 and 22 into the combustion cham-
ber 27. The consumed gas ejection from
and the fuel mixture charge injection into the
combustion chamber occurring during the
same stroke of the piston. Arc 78 represents
the secondary or combustion chamber fuel
compression period and arc 79 represents the
fuel ignition advance range.

From the relative position of arc 78 it is
evident that an extremely high fuel compres-
sion ratio may be used on this type engine
due to the fact that the fuel compression
within the combustion chamber 27 does not
commence until the crank journal is within
about 65 degrees of the outward or firing
dead center.

The invention herein described may be
manufactured and used by or for the Govern-
ment of the United States for governmental
purposes without the payment to me of any
royalty thereon or therefor.

Having fully described my invention I 105
claim:

1. In a combustion engine, the combination
of a piston with a plurality of concentric op-
erating surfaces separated by a cylindrical
surface and means integral with the last men-
tioned surface for permitting a gas to pass
along and through said piston, the said piston
being mechanically connected to a crank
shaft and each of said first mentioned sur-
faces operating within separate compart-
ments of uniform diameter throughout the
length of travel of the respective surfaces,
means associated with the cylindrical sur-
face of the said piston for controlling the in-
gress of fuel mixture into the larger of said
compartments from a source of supply, means
associated with the smaller of said surfaces
for controlling the ingress of said fuel mix-
ture into the smaller of said compartments,
means for controlling the egress of gases from
said smaller compartment, and means asso-
ciated with the said crank shaft for operat-
ing the last said means.

2. In a combustion engine as set forth in
claim 1, in which the means for controlling

the ingress of fuel mixture from a source of supply comprises a metal ring in contact with the cylindrical surface between the two operating surfaces and receiving a reciprocal motion therefrom, whereby ingress parts are alternately closed and opened.

3. In a combustion engine, the combination of a piston with a plurality of concentric operating surfaces separated by a cylindrical surface in which grooves and passageways are cut whereby a gas is allowed to pass along and through said piston, the latter being mechanically connected to a crank shaft and each of the first mentioned surfaces operating within separate compartments of uniform diameter throughout the length of travel of said respective surfaces, means associated with the larger of said compartments and associated with the grooved cylindrical surface of the said piston for controlling the ingress of fuel mixture into the larger of said compartments from a source of supply, means associated with the smaller of said surfaces for controlling the ingress of said fuel mixture into the smaller of said compartments, means for controlling the egress of gases from said smaller compartment, and means associated with the said crank shaft for operating the last said means.

4. In a combustion engine, a cylinder having an enlarged end bore portion, a piston reciprocable within the cylinder, said piston corresponding in length and diameter to the smaller bore portion of the cylinder, a piston head upon one end of the piston adapted to fit within the enlarged cylinder bore portion, whereby the movement of the piston away from the smaller bore portion produces a suction chamber about said piston, means carried by and slideable along the piston for permitting gaseous fuel to enter the suction chamber during the last named movement of the piston and whereby the movement of said piston directly operates the same and holds the same in each of its positions, said means also permitting compression of the gaseous fuel upon reverse movement of the piston, means secured to the cylinder for limiting the movement of said first named means, independent means permitting gaseous fuel to escape to the small cylinder bore portion when compressed in the larger cylinder bore portion, said last named means stopping the escape of gaseous fuel when the pressures in said cylinder bore portions are equalized, said piston and piston head having such ratios of compression that during the remainder of the reverse movement of the piston, after escape of gaseous fuel to the smaller bore portion ceases, the pressure developed in the smaller cylinder bore portion will exceed the pressure in the larger cylinder bore portion.

5. In a combustion engine, a cylinder having an enlarged end bore portion, a piston reciprocable within the cylinder, said piston

corresponding in length and diameter to the smaller bore portion of the cylinder, a piston head upon one end of the piston adapted to fit within the enlarged cylinder bore portion, whereby the movement of the piston away from the smaller bore portion produces a suction chamber about said piston, means carried by and slideable along the piston for permitting gaseous fuel to enter the suction chamber during the last named movement of the piston and whereby the movement of said piston directly operates the same and holds the same in each of its positions, said means also permitting compression of the gaseous fuel upon reverse movement of the piston means secured to the cylinder for limiting the movement of said first named means, independent means permitting gaseous fuel to escape to the small cylinder bore portions when compressed in the larger cylinder bore portion, said last named means stopping the escape of gaseous fuel when the pressures in said cylinder bore portions are equalized, an exhaust valve for the smaller cylinder bore portion, and means for closing said exhaust valve simultaneously with the moment of escape of the gaseous fuel from the larger cylinder bore portion to the smaller cylinder bore portion is stopped, said piston and piston head having such ratios of compression that during the remainder of the reverse movement of said piston after escape of gaseous fuel to smaller cylinder bore portion ceases, the pressure developed in the smaller cylinder bore portion will exceed the pressure developed in the larger cylinder bore portion.

6. In a combustion engine, a cylinder having an enlarged end bore portion, a piston reciprocable within the cylinder, said piston corresponding in length and diameter to the smaller bore portion of the cylinder, a piston head upon one end of the piston adapted to fit within the enlarged cylinder bore portion, whereby with movement of the piston away from the smaller bore portion produces a suction chamber about said piston, means carried by and slideable along the piston for permitting gaseous fuel to enter the suction chamber during the last named movement of the piston and whereby the movement of said piston directly operates the same and holds the same in each of its positions, said means also permitting compression of the gaseous fuel upon reverse movement of the piston means secured to the cylinder for limiting the movement of said first named means, independent means permitting gaseous fuel to escape to the smaller cylinder bore portion when compressed in the larger cylinder bore portion, said last named means stopping the escape of gaseous fuel when the pressures in said cylinder bore portions are equalized, said piston and piston head having such ratios of compression that during the remainder of the reverse movement of said piston, after escape of gaseous fuel to the smaller cylinder bore portion ceases, the pressure developed in the smaller cylinder bore portion will exceed the pressure in the larger cylinder bore portion.

of gaseous fuel to the smaller cylinder bore portion ceases, the pressure developed in the smaller cylinder bore portion will be more than twice the pressure developed in the larger cylinder bore portion.

5. 7. In a combustion engine, a cylinder having an enlarged end bore portion, a piston reciprocable in the cylinder, said piston substantially corresponding in length and diameter to the smaller bore portion of the cylinder, an enlarged piston head at one end of the piston adapted to fit the enlarged cylinder bore portion whereby with movement of the piston away from the smaller cylinder bore portion produces a suction chamber about said piston, means carried by and slidable along the piston for permitting gaseous fuel to enter the suction chamber during the last named movement of said piston and whereby the movement of said piston directly operates the same and holds the same in each of its positions, said means also permitting compression of the gaseous fuel upon reverse movement of the piston means secured to the cylinder for limiting the movement of said first named means, an independent means including a valve carried by the piston adapted to establish communication between the smaller cylinder bore portion and the suction chamber upon compression of gaseous fuel in said suction chamber and close said communication when the pressure of the gaseous fuel in said smaller cylinder bore portion becomes equal to the pressure of the gaseous fuel in the suction chamber, said piston and piston head having such ratios of compression that during the remainder of the reverse movement of said piston, after communication between the suction chamber and smaller cylinder bore is stopped, the pressure of the gaseous fuel in the smaller cylinder bore portion will exceed the compression of the gaseous fuel in the suction chamber.

8. In a combustion engine, a fuel inlet manifold, an inlet chamber in communication therewith, a cylinder, ports connecting the inlet chamber and cylinder, a power piston, a ring surrounding and in direct frictional engagement with said power piston and adapted to be moved thereby, said ring being adapted to close said ports when brought to a predetermined position and means secured to the cylinder wall for limiting the movements of the ring with respect to the piston whereby said ports may be maintained closed and open for certain intervals during each reciprocation of the piston.

9. In a combustion engine, a fuel inlet manifold, an inlet chamber in communication therewith, a cylinder, ports connecting the inlet chamber and cylinder, an elongated power piston, a ring yieldingly slidable in direct frictional contact with and along the said piston and adapted to close ports when brought to a certain position, means whereby the frictional contact between said ring and piston operates said ring, and means secured to the cylinder wall for limiting the movements of the ring with respect to said piston whereby said ports may be maintained closed and open for certain intervals with each reciprocation of the piston.

10. In a combustion engine, a fuel inlet manifold, an inlet chamber in communication therewith, a cylinder, ports connecting the inlet chamber and cylinder, a power piston, a ring frictionally slidable in direct contact with and along the piston and adapted to close ports when brought to a certain position means whereby the frictional contact between said ring and piston operates said ring and independent of said ring operating means adapted to maintain the ring in its port closing position during one stroke of the piston, and means independent of said ring for permitting the intake charge to enter the compression chamber of said cylinder.

11. In a combustion engine a fuel inlet manifold, an inlet chamber in communication therewith, a cylinder, ports connecting the inlet chamber and cylinder, a power piston, a ring frictionally slidable with and along said piston, and adapted to close ports when in a certain position means whereby the frictional contact between said ring and piston operates said ring, stationary means independent of said ring operating means adapted to maintain the ring in its port closing position during one stroke of the piston, and means including separate ports and independent of said ring for permitting the intake charge to enter the compression chamber of said cylinder.

12. In a combustion engine, a fuel inlet manifold, an inlet chamber in communication therewith, a cylinder, ports connecting the inlet chamber and cylinder, an elongated power piston, a ring frictionally slidable with and along said piston, and adapted to close ports when brought to a certain position, means whereby the frictional contact between said ring and piston operates said ring, and means for limiting the movement of said ring to only a portion of the movement of said piston, whereby said piston friction maintains said ring tight against its port as well as open according to the direction of movement of said piston, and means independent of said ring and including a separate port and a valve therefor for permitting the intake charge to enter the compression chamber of said cylinder.

13. In the method of charge intaking in combustion motors, the step of intaking a substantial portion of the charge in a plurality of very thin films in direct contact with the inner surface of the power cylinder.

14. In the method of charge intaking in combustion motors, the step of intaking a substantial portion of the charge in a plurality of

very thin films in direct contact with the inner surface of the power cylinder throughout a substantial portion of its length.

15. In the method of charge intaking in combustion motors, the step of intaking a substantial portion of the charge in a plurality of very thin films each separated by a thicker film and in direct contact with the inner surface of the power cylinder and with the outer surface of the piston.

16. In the method of charge intaking in combustion motors, the step of intaking a substantial portion of the charge in a plurality of very thin films each separated by a thicker film and in direct contact with the inner surface of the power cylinder and with the outer surface of the piston, and throughout a substantial portion of the length of said cylinder and piston, said thin and thicker films being at different velocities substantially throughout the intake cycle.

17. In the method of charge intaking in combustion motors, the step of overcoming crank-case dilution by transferring said dilution medium back into the power cylinder during the intake cycle by bringing the same into direct contact with the intake charge at a point adjacent the point of escape of said medium and the point where said charge enters the cylinder.

18. In the method of charge intaking in combustion motors, the steps of intaking a substantial part of said charge in a plurality of very thin films at substantial velocity, commingling the crank-case dilution medium with said films after said medium has passed the piston head, and conveying said medium back into the cylinder by the force of said films of the intake charge.

19. In the method of lubricating the pistons of motors, the step of passing a substantial portion of the main volume of the power producing medium in a plurality of very thin longitudinal films extending substantially about said piston between and in direct contact with an inner surface of the cylinder and an outer juxtaposed surface of the piston.

20. In the method of lubricating the pistons of combustion motors, the step of intaking a portion of the fuel charge in a plurality of thin films between and in direct contact with an inner surface of the cylinder and an outer juxtaposed surface of the piston.

21. In the method of lubricating and equalizing the temperature of the friction surfaces of pistons and cylinders, the step of passing power producing medium at substantial velocity between the juxtaposed surfaces of the cylinder and piston in a plurality of thin films each separated and connected by a thicker film.

22. In the method of cooling the cylinders and pistons of combustion motors, the step of transferring a substantial part of their heat to the intake charge of such motors by

passing a substantial part of said intake charge in a plurality of thin films at substantial velocity between and in direct contact with an inner surface of said cylinder and an outer surface of said piston.

23. In a motor, the combination of a cylinder, a piston and valve means therefor, of piston rings near opposite ends of said piston, and means whereby a portion of the fuel intake charge is admitted and passed at substantial velocity through an area between said oppositely located piston rings and the inner surface of the cylinder and an outer juxtaposed surface of said piston in a multiplicity of thin films.

24. In a combustion engine the combination with a cylinder, piston and valve means, of means for intaking a substantial portion of the charge in a plurality of very thin films in direct contact with the inner surface of the power cylinder.

25. In a combustion engine the combination with a cylinder, piston and valve means, of means for intaking a substantial portion of the charge in a plurality of very thin films in direct contact with the inner surface of the power cylinder and with the outer surface of the piston.

26. In a combustion engine the combination with a cylinder, piston and valve means, of means for intaking a substantial portion of the charge in a plurality of thin and thicker films of different velocities and in direct contact with the inner surface of said cylinder and with the outer surface of said piston.

27. In a combustion engine the combination with a cylinder, piston, crank, pitman, motive fuel vaporizing means and valve means, of means for conveying a substantial part of each motive fuel charge from said vaporizing means in a thin film in direct contact with substantially the whole inner surface of the power cylinder.

28. In a combustion engine the combination with a cylinder, piston, crank, pitman, motive fuel vaporizing means and valve means, of means for conveying a substantial part of each motive fuel charge from said vaporizing means in a thin film in direct contact with substantially the whole of the juxtaposed surfaces of said cylinder and piston.

29. In a combustion engine the combination with a cylinder, piston and valve means, of means for intaking the charge and leading the same into bodily contact with the crank case dilution medium at a point adjacent the points of escape of said medium and where said charge enters said cylinder.

30. In a combustion engine the combination with a cylinder, piston and valve means, of means for intaking a substantial part of the charge in a plurality of very thin films of substantial velocity, and means for commingling the crank case dilution medium

with said film after said medium has passed the piston head.

31. In a combustion engine the combination with a cylinder, piston, crank, pitman, valve means, and a crankcase adapted to contain a supply of lubricant, of means separating the charge from said lubricant and for intaking a substantial part of said charge past and in contact with one of said elements contacted by said lubricant for effecting a substantial reduction in temperature of said lubricant.

32. In a combustion engine the combination with a cylinder, piston, crank, pitman, valve means, a crankcase adapted to contain a supply of lubricant, and motive fuel vaporizing means, of means separating the charge from said lubricant and for intaking a substantial part of said charge from said vaporizing means past and in contact with one of said elements contacted by said lubricant for effecting a substantial reduction in temperature of said lubricant.

33. In a combustion engine the combination with a cylinder, piston, crank, pitman, valve means and a crankcase adapted to contain a supply of lubricant, of means including thermal communicating surfaces of a portion of one of said elements, some of which surfaces being contacted by said lubricant and separating the charge from said lubricant and for intaking a substantial part of said charge past and in contact with one or more others of said surfaces for effecting a substantial reduction in temperature of said lubricant.

34. In a method of reducing the temperature of the lubricant of a combustion engine having a supply of lubricant adapted to contact with heated portions of said engine, the steps of intaking the fuel charge separate from said lubricant supply and passing a substantial portion of said charge in such thermal association with said lubricant as to effect a substantial reduction in the temperature of said lubricant supply.

35. In the method of reducing the temperature of the lubricant of a combustion engine having a supply of lubricant adapted to contact with heated portions of said engine, the steps of intaking in said engine a mixed charge of air and liquid fuel separated from said lubricant supply, and passing a substantial portion of said charge in such thermal association with said lubricant as to effect a substantial reduction in the temperature of said lubricant supply.

FRANK DAVID BUTLER.
